COIL PACKAGING

John W. Adams, Bradley Beach, N. J.

Application April 3, 1950, Serial No. 153,683

8 Claims. (Cl. 206—59)

(Granted under the act of March 3, 1883, as amended April 30, 1928; 370, O. G. 757)

1

The invention described herein may be manufactured and used by or for the Government for governmental purposes, without the payment to me of any royalty thereon.

This invention relates to the packaging of wire, particularly to the packaging of wire which is wound into a coil having a hollow center so that it may be paid out from said hollow center.

In the present application, the invention will be illustrated in connection with coils of insulated electrical wire for telephone and telegraphic communication, but it will be understood that the invention is applicable to many other elongated coilable materials, such as rope, twine, flexible tubular conduit for electrical wires, multiple conductor cables, uninsulated wire, or any type of flexible stranded wire, rope, etc., and hence should not be deemed to be limited to the illustrated embodiment.

In conventional usage, cable or wire to be paid out is unwound from a spool or reel which is rotated about its axis during the paying out operation. It is apparent that such method and the conventional devices employed have numerous disadvantages, among which are the requirement of the use of heavy and unwieldy equipment, the difficulty in laying or paying out of the wire at a relatively high speed because of the friction and inertia that must be overcome, and that, in paying out from spools or reels, intermittent operation is mandatory, that is, the paying out of the wire will stop at the termination of the wire in each spool.

In an attempt to overcome the objections to the use of wire wound upon spools or reels, there have been devised various means of winding cable or wire wherein the wire is not wound upon a spool or reel but is wound with a hollow center so that the wire is paid out from the inside of the coil.

Packages of wire so wound were usually encased in metal or wooden containers, which containers had an opening on one side through which the wire was paid out. It has, however, been found that in practice, certain limitations were imposed by the use of metal or wooden containers for packaging coils of wire. Thus, it was found that in time of material shortages, production of wire coils so packaged would be hampered if the use of metal or wood was critical. It was also discovered that metal or wooden containers could not be dropped any distance without the possibility of damage to or partial destruction of the container so as to make the wire unusable.

It is therefore an object of the present invention to provide a package for a coil of wire or the like, that is lighter in weight and smaller in size than containers previously used, and therefore easier to handle, transport and store.

Another object of the invention is to provide a package for a coil of wire or the like, which is shock resistant, so that in the event of being dropped, no resultant damage to the package or the wire contained therein will occur.

It is a further object of the invention to provide a packaging means wherein the size and length of the wire to be coiled and packaged need not be rigidly predetermined, inasmuch as the packaging means herein described can be used for coils of various lengths and sizes.

These and other objects and advantages of my invention will be better understood when read in the light of the following description and the annexed drawing in which:

Fig. 1 is a view in perspective of a coil of wire which has been packaged according to the present invention, with parts of the package being broken away to illustrate the steps of assembly and details of the preferred construction.

Fig. 2 is an elevational view of one of the flexible end members of my packaging means; and

Fig. 3 is an elevational view of a coil of wire being wound upon a mandrel.

In packaging a coil of wire according to my invention, the wire 11 is wound upon a mandrel 13 between two spaced opposing end members 15 which are positioned against stiff flanges 17 which support said end members during the winding and packaging operation.

The axial dimension of the coil is determined by the position of the end members 15 and stiff flanges 17 upon the mandrel 13. Each end member 15 is preferably made of a strong flexible material such as heavy canvas and includes a substantially circular body 19 from the circumference of which extend a plurality of radially disposed tabs 21. A central payout opening 23 is provided at the center of the body 19 which opening is preferably surrounded by a metal or rubber grommet 25 which will resist the wear resulting from paying out the wire.

After the parts are positioned as explained, the wire or cable 11 is wound upon the mandrel 13 until the coil reaches any desired outside diameter. Preferably I place a cover 27 about the mandrel before the winding of the wire 11 upon it, to make it easier to remove the packaged coil therefrom. The cover 27 may be of any suitable material, but I prefer a tubular sleeve of leather.

The wire 11 may be wound in any desired fashion such as "criss-cross," "level layer wound," "honeycomb," etc., the particular winding process not being a part of the present invention.

After the coil of wire is wound to its desired size, a first layer 29 of double coated tape (that is, tape which is provided with adhesive, so as to be tacky, on both surfaces) is wound about the entire cylindrical surface of the coil of wire. The tackiness of the surface of the tape facing the outer layer of wire of the coil, is of such a degree of adhesiveness as to retain or hold the outer layer of wire in position, but at the same time permit the said outer layer of wire to be drawn off from the layer of tape when desired during the payout operation. The tabs or fingers 21 of one of the end members 15 are then bent inwardly over said first tape layer 29 to form a second layer 30. At the time of the positioning of the tabs 21 as set forth, in forming layer 30, one of said tabs is first threaded through a D-shaped metal ring 31 for the purposes hereinafter set forth. If desired, several such rings 31 may be positioned at various points about the periphery of the package.

A third layer 33 of double coated tape is then wound over said second layer 30 (of tabs 21) and the exposed portions of the first tape layer 29. The next step in the fabrication of a package is to fold or bend the tabs 21 of the other end member 15 to form a fourth layer 34 over the third layer 33 (of tape). There is then wound a fifth layer 35, also of double coated tape, over the fourth layer 34 and the exposed portions of the third layer 33.

While in Figure 1 of the drawing the tabs or fingers 21 of one of the end members 15 are shown as slightly spaced from the tabs of the other end member, for purposes of clarity, it has been found that in the actual assembly of the package, the best results are secured when the tabs are of such width and are so oriented that the tabs of the two end members interdigitate with each other though separated by the third tape layer 33. Thus it is seen that the two sets of tabs 21, so interdigitated, form a sheath of canvas (or other like strong flexible material) encircling the lateral surface of the coil of wire. Part of said canvas sheath is between the first and third layers 29, 33 and the balance of said canvas sheath is between said third and fifth layers 33, 35.

It is to be understood that I do not limit myself to the shape and number of tabs as shown in the drawing, as it may be desired to have the tabs 21 of each end member 15 so close to each other that said tabs form a complete rather than a partial covering when folded over the lateral surface of the coil.

The package is then completed by applying a sixth layer 37 of single coated tape (which is tape that is tacky only on the inwardly facing surface) completely about the fifth layer 35. It is obvious, that in applying the tape of the aforementioned layers, said tape will by-pass the D-shaped ring 31 or rings. The rings serve as a means for supporting the package when it is desired, as during the payout operation.

While there has been described in the specific embodiment a series of sequential steps in the assembly of the package, it is obvious that variations in the assembly can be made. For example, the tab layers can first be applied to the outer lateral surface of the coils and then a single or plurality of tape layers can be wound or other

variations in the steps of assembly can be similarly accomplished.

Packaged coils of wire as described herein can be paid out in tandem as described in Patent No. 2,490,837 issued December 13, 1949.

While there has been herein described what is considered the preferred embodiment of my invention, it will be obvious to those skilled in the art that changes and modifications may be made without departing from my invention.

What is claimed is:

1. A package, for a coil having a hollow center, comprising two end members at least one of said members having a central opening, each of said members including a body portion having an outside diameter substantially equal to that of said coil and having a plurality of radially disposed tabs about the circumference of said body portion, and first, second, third, fourth, fifth and sixth layers disposed successively about the outer lateral surface of said coil, said first layer being of tape and covering the outer lateral surface of said coil, said second layer comprising the tabs of one of said end members and at least partially covering said first layer, said third layer being of tape and covering said second layer and any exposed portions of said first layer, said fourth layer comprising the tabs of the other of said end members and at least partially covering said third layer, said fifth layer being of tape and covering said fourth layer and any exposed portions of said third layer, and said sixth layer being of tape and covering said fifth layer.

2. A package of the type described in claim 1, which includes means for suspending said package, said means including a ring and one tab of each of said end members, said two tabs extending through said ring from opposite directions and being superimposed.

3. A package as defined in claim 1, wherein the tape of the first, third and fifth layers is provided with adhesive on both surfaces and the tape of the sixth layer is provided with adhesive on its inner surface.

4. A package, for a coil having a hollow center, comprising two end members, each of said members including a circular body portion having an outside diameter substantially equal to the diameter of said coil and having a plurality of radially disposed tabs about the circumference of said body portion, said tabs extending over the outer lateral surface of said coil, and a side member which covers the lateral surface of said coil and grips said tabs.

5. A package, for a coil of strand material, comprising two end members, each of said end members including a circular body portion having an outside diameter substantially equal to the diameter of said coil and having a plurality of radially disposed tabs about the circumference of said body portion, and a lateral member, said lateral member including a plurality of layers about the lateral surface of said coil, said layers including at least one layer comprising a plurality of turns of tape and said layers gripping said tabs.

6. The method of forming a packaged, hollow center, coil of strand material, comprising the steps of winding said strand material upon a mandrel between two end members to form a coil of said material, each of said end members comprising a substantially circular body having a payout opening therein and a plurality of radially disposed tabs extending from the circumference thereof, wrapping a first layer of tape

over the outer lateral surface of said coil, bending the tabs of one of said end members over said first layer to form a second layer, wrapping a third layer of tape over said first and second layers, bending the tabs of the other of said end members over said third layer to form a fourth layer, wrapping a fifth layer of tape over said third and fourth layers and wrapping a sixth layer of tape over said fifth layer.

7. The method of forming a packaged coil of strand material, comprising the steps of winding said strand material on a mandrel between two end members to form a coil of said material, each of said end members comprising a substantially circular body and a plurality of radially disposed tabs extending from the circumference thereof, bending said tabs over the outer lateral surface of said coil and applying at least one tape layer over said tabs.

8. The method of forming a packaged coil of strand material comprising the steps of winding said material upon a mandrel between two end

members to form a coil of said material, each of said end members comprising a substantially circular body of a diameter substantially equal to that of said coil and an extending portion, wrapping a first layer of tape over the lateral surface of said coil, bending said extended portion of one of said end members over said first layer to form a second layer, wrapping a third layer over said first and second layers, bending the other of said extended portions over said third layer to form a fourth layer and applying at least one additional layer over said fourth layer.
